Fraenkel & Richards,
ATTORNEYS

UNITED STATES PATENT OFFICE.

ABRAM W. WHEATON, OF NEWARK, NEW JERSEY.

SELF-CLOSING VALVE.

1,322,076.

Specification of Letters Patent. Patented Nov. 18, 1919.

Application filed August 2, 1919. Serial No. 314,831.

To all whom it may concern:

Be it known that I, ABRAM W. WHEATON, a citizen of the United States, residing at Newark, in the county of Essex and State 5 of New Jersey, have invented certain new and useful Improvements in Self-Closing Valves; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in faucets, particularly adapted for use upon oil and gasolene tank vehicles; and the invention relates, more particularly, to an improved self-closing 20 faucet and detachable operating handle for manipulating the same.

The invention has for its principal object 25 to provide a novel construction of self-closing faucet adapted to be manipulated by a detachable handle, said faucet being further provided with a novel means coöperating with a portion of the valve stem of the faucet to hold the valve open to full or 30 partial extent or capacity, said means being also adapted, when properly manipulated, to engage the valve stem in such a manner when the valve is closed, as to prevent operation or opening of the same by the manipulating handle, an additional locking hasp 35 and lock device being employed to retain said means in such valve locking position.

Other objects of the present invention, not at this time more particularly enumerated, will be clearly understood from the 40 following detailed description of the same.

With the various objects of the invention in view, the same consists, primarily, in the novel self-closing faucet hereinafter set forth; and the invention consists, further- 45 more, in the novel arrangements and combinations of the various devices and parts, as well as in the details of the construction of the said parts, all of which will be more fully described in the following specification, and then finally embodied in the claims 50 which are appended to and which form an essential part of the said specification.

The invention is clearly illustrated in the accompanying drawings, in which:

55 Figure 1 is a vertical longitudinal section

of the novel self-closing faucet, showing the detachable handle applied thereto, and further illustrating in dotted outline the valve in opened position, together with the retaining means for holding said valve in said open 60 position.

Fig. 2 is a detail top end view of the novel faucet.

Fig. 3 is a detail vertical longitudinal section of the upper end of the faucet, illustrating the retaining means positioned to lock the valve stem and its valve against manipulation.

Similar characters of reference are employed in all of the hereinabove described 70 views, to indicate corresponding parts.

Referring now to said drawings, the reference character 1 indicates the faucet body providing in its lower end the interior chamber or passage 2. Extending from the rear 75 side of said faucet body is an internally screw-threaded extension 3 communicating with said chamber or passage 2, and adapted to receive the threaded end of the outlet pipe of the tank vehicle (not shown), thus 80 securing the faucet operatively thereto. Connected with the lower end of said faucet body is a downwardly extending nozzle-portion 4, externally threaded at 5 to receive a hose-connection (not shown) when desired. 85 Said nozzle-portion 4 is provided within said faucet body with a valve-seat 6, upon which seats itself, when in closed position, a vertically movable valve member 7, upon which is secured a valve washer 8 of suitable 90 material. Connected with said valve member 7 is an upwardly extending valve stem 9. Connected with the upper end of said faucet body 1 is an upwardly extending part 10 having a centrally disposed opening forming a guideway 11 through which said valve stem 9 slidably extends. Said part 10 is connected at its upper end with a chambered extension 12 providing an internal chamber 13, closed at its upper end by a cap-plate 14 100 suitably secured in place by fastening screws 15, or any other desirable fastening means. Formed in the upper end of said part 10, at the juncture thereof with said extension 12, is an annular depression forming a packing seat 16, in which is arranged a suitable packing 17, adapted to embrace said valve stem 9, and thereby prevent leaking of any fluid upward through said guideway 11. A perforate keeper plate 18, se- 110

55 Figure 1 is a vertical longitudinal section

cured to the bottom of said extension 12, by screws 19, or other suitable fastening means, serves to retain said packing 17 against removal from said packing seat 16.

5 Arranged about said valve stem 9, between the upper wall of said faucet body 1 and said valve member 7, is a spiral compression spring 20, the tension or pressure of which is exerted downwardly upon said 10 valve member 7 to hold the same with its washer 8 in closed or seated relation to the valve seat portion 6.

Said valve stem 9 projects upwardly into the chamber 13 of said extension 12, and 15 is provided adjacent to its upper end with a transverse slot or receiving opening 21. Extending upwardly from the upper extremity of said valve stem 9 is a reduced extension 22 thereof, which is slidably disposed for vertical movement in a guideway 23 provided in said cap-plate 14. Formed in the front side of said extension 12 is an opening or gateway 24, providing access to the valve stem 9 for the detachable operating handle or lever 25. The lower end of said opening or gateway 24 is formed to provide a knife-edge fulcrum member 26, which engages in a pivot notch 27 provided in the body of said handle or lever 25, when 30 the latter is thrust through said opening or gateway for operative engagement with said valve stem 9. Pivoted to the exterior surface of said extension 12 is a closure member or shutter 28 which falls by gravity 35 over said opening or gateway 24, when the handle or lever 25 is withdrawn, to thereby close said opening or gateway 24 against the entrance of dirt, dust or other objectionable foreign substances into the valve stem 40 inclosing chamber 13.

Fixed upon said cap-plate 14, preferably as an integral part thereof, are a pair of perforate upstanding ears 29, alined with and positioned one on either side of the 45 outwardly projecting end of said reduced extension 22 of said valve stem 9. Pivoted to said ears 29, by means of its depending side lugs 30 is a transverse stop member or retaining plate 31, the same being provided 50 at its rear edge with a chamfered catch-lip 32. Integrally connected with the forward edge of said stop member or retaining plate 31 is an outwardly extending tongue or arm 33, secured to which, adjacent to its free 55 end, is an off-set eye-member 34. Said reduced extension 22 of said valve stem 9 is provided, in its outwardly projected free end portion, and on the front side of the latter, with one or more notches or indentations 35.

That portion of said valve stem 9 which moves in the part 10 is provided, at one side, with an elongated depression or groove 36. A stop-screw 37 is passed through the wall 65 of the part, so that its end enters said de-

pression or groove 36. Said stop-screw prevents turning or axial rotation of the valve stem 9 tending to displace the receiving opening 21 of the latter, or the notches or indentations 35 of the reduced extension 22, 70 from their respective operative locations relative to the opening or gateway 24 in the one case, or to the path of movement of the catch-lip 32 of the retaining plate 31 in the other case, while at the same time the 75 length of the depression or groove 36 provides adequately for the longitudinal movement of the valve stem 9 accompanying the operations of opening and closing the valve member 7.

To operate or open the faucet it is necessary to impart an upward movement to the valve stem 9 to lift the valve member 7 and its washer 8 from the valve seat portion 6, against the tension of the spring 20, thereby 85 allowing the fluid entering the faucet to pass outward through the nozzle-portion 4. To so operate the parts the handle or lever 25 is inserted through the gateway 24, so that its inner end enters said receiving opening 21 90 of the valve stem 9, and so that its pivot notch 27 is fulcrumed upon the fulcrum member 26 at the bottom of said gateway 24. When the handle or lever 25 is thus operatively related to the faucet, a downwardly 95 swinging movement is imparted to the outwardly projecting free end of the same, which swings upwardly, the inner end thereof, and consequently causes the said inner end to engage the valve stem 9 and thereupon impart thereto an upward sliding movement which raises the valve member 7 and its washer 8 clear of the valve seat portion 6, so as to permit the fluid to pass by said valve member and thence be discharged 100 from said faucet through said nozzle-portion 4.

If it be desired to hold the faucet valve in open position, the following operations are effected. Normally the retaining plate 110 31 swings downward in front of the outwardly projected end of said reduced extension 22 of the valve stem 9, so as to clear the same, and permit free upward movement thereof when the valve stem 9 is raised in 115 opening the faucet. In this position the arm 33 of the retaining plate projects outwardly and forwardly (as shown by the full line representation of the same in Fig. 1). After the valve-stem 9 is raised by the 120 manipulation of the handle or lever 25, as above described, the arm 33 is swung upwardly, causing said retaining plate 31 to swing upwardly upon its pivotal connection, so that the chamfered catch-lip 32 of the 125 same is carried into engagement with one or the other of the notches or indentations 35 of the reduced extension 22, as shown by the dotted representation of the parts in Fig. 1. The catch-lip 32 being engaged with one 130

of the notches or indentations 35 of said reduced extension 22, serves to retain said extension and consequently the valve stem 9 and valve member 7, against downward movement under the impulsion of the spring 20, and consequently the faucet remains open. The handle or lever 25 may be removed or withdrawn while the faucet is thus held open. When it is desired to close the faucet again, the arm 33 is pressed or swung downward, which in turn causes a downward swinging movement of said retaining plate 31 on its pivotal connection, so that the catch-lip 32 is swung outwardly and away from the engaged notch or indentation 35, whereupon the tension or compression of the spring 20 will impel said valve member 7 with its washer 8 downward to seated relation with the seat-portion 6 thereby again closing the faucet against the discharge of fluid therethrough. The amount of opening or lift imparted to the valve member 7 and its washer 8 determines the amount of flow capacity through the faucet, consequently the plurality of notches or indentations 35 may be utilized by selection to hold the faucet open to the desired degree.

If it is desired to arrange the faucet so that the same is entirely self-closing, and rendered impossible to be retained in open condition in the manner above described, the stop-screw 37 is withdrawn from the elongated depression 36, so that the valve-stem 9 may be given a half turn, and then again secured against axial rotation. The half turn given to the valve-stem turns the notched or indented face of the reduced extension 22 away from its operative forwardly facing position, in other words to the rear, in which changed position the notches or indentations 35 are no longer presented in position to receive the catch-lip 32 of the retaining plate 31, and consequently the latter is rendered inoperative to hold the faucet open in the manner above described, so that as soon as the valve opening pressure imparted through the agency of the handle or lever 25 is released, the spring 20 will immediately close the valve member 7, as will be understood.

It is often desirable to lock the faucet against any manipulation by the handle or lever 25 or other means, particularly when putting up for the night the tank vehicles upon which the faucets are used. To this end the novel retaining plate 31 is designed and arranged to cooperate with a locking means in the following manner, and by the following means.

When the valve-member 7 and its washer 8 is seated upon the valve seat-portion 6, and the valve stem 9 with its reduced extension 22 moved to its downward limit, said retaining plate 31 is capable of being swung over

the upper extremity of said reduced extension 22, so as to obstruct any upward movement thereof, and consequently prevent any rising or opening movement of the valve stem and valve member. In order to hold the retaining-plate 31 in such obstructing position, there is provided a swinging hasp-plate 38, which is pivoted to a perforated ear 39, the latter having a screw threaded shank 40, whereby the same is screwed into fixed relation to said cap-plate 14 and said extension 12. The free end of said hasp-plate 38 is provided with a hasp-slot 41. When the retaining plate 31 has been positioned in obstructing relation to the reduced extension 22, said hasp-plate 38 is swung upwardly so that its hasp-slot 41 is caused to pass over said offset eye-member 34 of the arm 33 of said retaining plate 31. A pad-lock 42, or other suitable locking device is thereupon secured through the eye-member 34 so as to prevent separation of said hasp-plate and said arm 33, thereby locking and holding said retaining plate in obstructing position relative to said reduced extension 22, all as indicated more clearly in Fig. 3 of the accompanying drawings.

The reference character 43 indicates a horn or spur projecting from the front side of the valve body 1, and serving to support the bail of a can or other receptacle in suspended position beneath the nozzle-portion 4 while being filled.

I am aware that some changes may be made in the several arrangements and combinations of the various devices and parts, as well as in the details of construction of the same, without departing from the scope of the present invention as set forth in the foregoing specification, and as defined in the appended claims. Hence, I do not limit my invention to the exact arrangements and combinations of the several devices and parts described in the foregoing specification, nor do I confine myself to the exact details of the construction of the said parts as illustrated in the accompanying drawings.

I claim:—

1. The combination with a faucet body of a self-closing valve having an upwardly extending stem, the upper free end of said stem projecting exteriorly of said faucet body, the exteriorly projecting end of said stem having an indented notch in one side thereof, a retaining plate, means for pivoting said retaining plate in connection with said faucet body so that the same may be swung over the exteriorly projecting end of said stem when the valve is closed, an arm projecting outwardly from said retaining plate having an off-set eye-member, a hasp-plate pivotally connected with said faucet body to swing into embracing relation to said eye-member when said retaining plate is moved to valve stem obstructing position, 130

- said eye-member being adapted to receive a locking means whereby said hasp-plate and said retaining plate arm are secured together, said retaining plate being further 5 provided in its rearward edge with a chamfered catch-lip adapted to be engaged in said indented notch of said stem when the latter is raised to hold said valve in opened position, and means for raising said stem.
- 10 2. The combination with a faucet body of a self-closing valve having an upwardly extending stem, the upper free end of said stem projecting exteriorly of said faucet body, a retaining plate, means for pivoting 15 said retaining plate in connection with said faucet body so that same may be swung over the exteriorly projecting end of said stem when the valve is closed, an arm projecting outwardly from said retaining plate having 20 an off-set eye-member, a hasp-plate pivotally connected with said faucet body to swing into embracing relation to said eye-member when said retaining plate is moved to valve stem obstructing position, said eye-member being adapted to receive a locking means whereby said hasp-plate and said retaining plate arm are secured together. 25
3. The combination with a faucet body of a self-closing valve having an upwardly extending stem, the upper free end of said stem having a notch in one side thereof, a retaining plate pivoted to said faucet body, said retaining plate having at its rearward edge a chamfered catch-lip engageable 30 in said notch when said stem is raised to valve opening position, said retaining plate being engageable against the free end of said stem when the latter is lowered to valve closing position, and means for locking said 35 retaining plate in the latter position.
4. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap- 40 plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly 45 extending portion projecting exteriorly through said cap-plate, a retaining plate, means for pivoting said retaining plate upon said cap-plate so that the same may be swung over the extremity of said upwardly 50 extending stem portion to obstruct the opening movement of said valve and its stem, an arm projecting outwardly from said retaining plate having an off-set eye-member, and a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 55
- 60 5. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap-plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly extending portion projecting exteriorly through said cap-plate, said upwardly extending portion having an indented notch in one side thereof, a retaining plate, means for pivoting said retaining plate upon said cap-plate so that the same may be swung over the extremity of said upwardly extending 65 stem portion to obstruct the opening movement of said valve and its stem, an arm projecting outwardly from said retaining plate having an off-set eye-member, a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 70
- 75 6. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap-plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly 80 extending portion projecting exteriorly through said cap-plate, a retaining plate, means for pivoting said retaining plate upon said cap-plate so that the same may be swung over the extremity of said upwardly extending stem portion to obstruct the opening movement of said valve and its stem, an arm projecting outwardly from said retaining plate having an off-set eye-member, and a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 85
- 90 7. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap-plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly 95 extending portion projecting exteriorly through said cap-plate, a retaining plate, means for pivoting said retaining plate upon said cap-plate so that the same may be swung over the extremity of said upwardly extending stem portion to obstruct the opening movement of said valve and its stem, an arm projecting outwardly from said retaining plate having an off-set eye-member, and a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 100
- 105 8. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap-plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly 110 extending portion projecting exteriorly through said cap-plate, a retaining plate, means for pivoting said retaining plate upon said cap-plate so that the same may be swung over the extremity of said upwardly extending stem portion to obstruct the opening movement of said valve and its stem, an arm projecting outwardly from said retaining plate having an off-set eye-member, and a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 115
- 120 9. The combination with a faucet body of a self-closing valve having an upwardly extending stem, said faucet body having a chambered extension at its upper end, a packing seating portion intermediate said chambered extension and said faucet body through which said stem extends to the interior of said chambered extension, a cap-plate for closing the upper end of said chambered extension, said stem having a transverse receiving slot adjacent to its upper end, said chambered extension having an opening in its side wall opposite said receiving slot of said stem, a detachable lever for insertion through said opening into operative relation to said receiving slot of said stem, means for preventing axial rotation of said stem, said stem having an upwardly 125 extending portion projecting exteriorly through said cap-plate, a retaining plate, means for pivoting said retaining plate upon said cap-plate so that the same may be swung over the extremity of said upwardly extending stem portion to obstruct the opening movement of said valve and its stem, an arm projecting outwardly from said retaining plate having an off-set eye-member, and a hasp-plate pivotally connected with said cap-plate to swing into embracing relation to said eye-member when said retaining plate is moved to valve stem obstructing position, said eye-member being adapted to receive a locking means whereby said hasp-plate and retaining plate arm are secured together. 130

ing slot of said stem, a detachable lever for insertion through said opening into operative relation to said receiving slot of said stem, means for preventing axial rotation 5 of said stem, said stem having an upwardly extending portion projecting exteriorly through said cap-plate, said upwardly extending portion having an indented notch in one side thereof, a retaining-plate, means 10 for pivoting said retaining plate upon said cap-plate, and said retaining plate having at its rearward edge a chamfered catch-lip adapted to be engaged with said indented notch of said upwardly extending stem-portion when the latter is raised to hold said 15 valve in opened position.

In testimony that I claim the invention set forth above I have hereunto set my hand this 24th day of July, 1919.

ABRAM W. WHEATON.
